AUTO DEFROSTER

Hajime Ota, Tokyo, Japan, assignor to Fedtro, Inc., a corporation of New York

Filed Oct. 22, 1965, Ser. No. 87,772

Term of patent 14 years

(Cl. D14—6)

FIG. 1 is a front elevational view of an auto defroster showing my new design;

FIG. 2 is a rear elevational view;

FIG. 3 is a left side view;

FIG. 4 is a right side view;

FIG. 5 is a bottom plan view; and

FIG. 6 is a top plan view thereof.

The wire is shown broken away in FIGS. 1, 2, 3 and 4 to illustrate indeterminate length.

I claim:

The ornamental design for an auto defroster, substantially as shown and described.
